UNITED STATES PATENT OFFICE.

HERMAN C. PRIEBE, OF BLUE ISLAND, ILLINOIS.

DRAFT GEAR.

Application filed April 17, 1922. Serial No. 554,242.

To all whom it may concern:

Be it known that I, HERMAN C. PRIEBE, citizen of the United States, residing at Blue Island, in the county of Cook and State 5 of Illinois, have invented a certain new and useful Improvement in Draft Gears, of which the following is a full, clear, concise, and exact description.

My invention relates to railway cars and 10 to draft gears employed therein.

The invention has for one of its objects the unification of draft gear carriers and draft lugs in integral structures. This characteristic of my invention has been of particular service in connection with freight cars having wooden center sills. In such a car I employ two angle irons each having an inner upright and a lower outwardly extending side, each angle iron being individual to and receiving one of the two center sills of the car at the lower inner longitudinal corner of such sill. There are two carriers for each draft gear, these carriers underlying and being fastened to the lower 25 sides of the corresponding angle irons. There are also inner and outer draft lugs that are fastened to the upright sides of the angle irons. Each angle iron has thus assembled therewith a structure individual 30 thereto and comprising a carrier and inner and outer draft lugs, each carrier and the corresponding draft lugs being formed in one piece.

The draft gear carrier portions are desirably inwardly extended into abutting engagement with the adjacent body bolster that thus reinforces the inner draft lugs in resisting draft strains.

The invention also relates to those draft 40 gears which employ keys for assembling coupler shanks with the balance of the draft gears. In car structures having such draft gears the center or draft sills are formed with openings through which the keys are passed in the process of placing them in position. These keys project laterally of the 45 sills and there are cotter pins or other formations to keep them from becoming dislodged.

In accordance with my invention the draft 50 sills may be provided with the usual openings to permit of the passage of keys therethrough. I am enabled to make these keys sufficiently short to occupy the space between 55 the adjacent sills without projecting through the sills. In order to prevent the keys from

becoming dislodged the openings in the sills through which they are passed are sufficiently covered by obstructions to prevent the withdrawal of the keys.

I will explain my invention more fully by reference to the accompanying drawings in which Fig. 1 is a plan view, with parts shown in section and parts broken away, of a portion of a car structure having equipment of my invention applied thereto; Fig. 2 is a sectional view on line 2—2 of Fig. 1 with the assumption that some of the parts not shown in Fig. 1 are present; Fig. 3 is a sectional view on line 3—3 of Fig. 1; Fig. 4 is a sectional view on line 4—4 of Fig. 1; Fig. 5 is a perspective view illustrating two draft lugs and a carrier formed integrally with each other in the same casting; and Fig. 6 is a sectional view on line 6—6 of Fig. 2.

Like parts are indicated by similar characters of reference throughout the different figures.

I have illustrated enough of the under frame of a freight car structure to show the relation of my invention thereto. This underframe includes longitudinal wooden sills 1 and 2 which are cut away at their outer ends to receive wooden end sills, the end sill 3 at one end of the car structure being illustrated. There are two angle irons at each end of the car structure, each angle iron having an inner upright side 4 and a lower outwardly extending side 5. Each angle iron is individual to a center sill, such sill being received in the angular seat of the corresponding angle iron at the lower inner longitudinal corner of such sill. Each center sill thus includes the wooden sill and the angle iron in addition thereto.

There is a draft gear carrier 6 individual to each angle iron, each carrier underlying and being fastened to the lower side of its angle iron. The means for fastening the carriers to their angle irons are desirably in the form of rivets 7 which pass through rivet holes 8 in the carriers and through corresponding rivet holes in the bottom walls of the angle iron. There are also inner and outer draft lugs 9 and 10 at each end of the car structure, each carrier having an inner lug and an outer lug formed in the same integral casting therewith. These draft lugs are formed with rivet holes 11. Rivets 12 are passed through these rivet holes and through corresponding rivet holes in the adjacent upright sides of the angle irons.

Each carrier has two depressions 13 for receiving keys 14 that pertain to the draft gear. These keys project outwardly beyond the center sills, the outer ends of these keys 5 being surrounded by spring abutments 15 that are provided for the motor resisting springs 16 upon the exterior of the sills. These keys also pass through followers 17 and 18 that are disposed between the sills, 10 there being a longitudinal spring 19 between and abutting the followers. A coupler yoke 20 surrounds the followers, this yoke being of U-form, each end of the yoke being bifurcated into fork branches 21. The coupler 15 includes a coupler shank 22 whose inner end abuts the outer follower 17. This coupler is assembled with the coupler yoke by means of the key 23 that is passed through registering slots in the coupler shank 22 and 20 the forked branches 21 of the coupler yoke. Carriers 6 also preferably constitute draft sills, being outwardly extended beyond the region of the key 23 and having slots 24 formed therein through which the key 23 25 may be passed through the registering slots in the coupler portion 22 and the yoke parts 21.

Hitherto these keys have projected outwardly beyond the draft sills through 30 which they were passed, but in accordance with my invention such a key is shortened to be fully confined in the space between these draft sills, the openings 24 being afterwards sufficiently covered by obstructions 25 to prevent of the repassage of the key therethrough. These obstructions are 35 preferably in the form of angle irons while both draft sills are formed with the openings 24 which have to be closed by the obstructions 25, yet it is obvious that but one 40 of these draft sills needs to be provided with such an opening. It will be observed that the obstruction 25 lies against the inner upright face of the draft sill to which 45 it is applied and substantially to one side of this face whereby the key receiving opening in this sill may be readily uncovered when it is desired to remove the key.

50 Each composite draft sill and draft gear carrier 6 has integrally formed therewith in the same casting outer and inner draft lugs 9, 10, the outer draft lugs being engaged by the follower 17 and the inner draft lugs being engaged by the follower 18. At each end of the car there is a body bolster 28. The carrier portions 6 of the carrier-draft lug castings are inwardly continued into abutting engagement with 55 the corresponding bolster whereby the bolster and the draft sills co-operate with the inner draft lugs in resisting coupler blows.

60 It is apparent to those skilled in the art that the structure of my invention, when 65 employed in connection with car under-

frames having wooden center sills, greatly increases the strength of such underframes. The various advantages of my invention will be readily understood from the foregoing description and accompanying illustrations.

While I have herein shown and particularly described the preferred embodiment of my invention I do not wish to be limited to the precise details of construction shown 75 as changes may readily be made without departing from the spirit of my invention, but having thus described my invention I claim as new and desire to secure by Letters Patent the following:—

1. In a car structure, the combination with a draft gear; of two wooden center sills; two angle irons each having an inner upright and a lower outwardly extending side and individual to and receiving one of said sills at the lower inner longitudinal corner of such sill; and a structure individual to and carried by each angle iron and comprising a carrier for the draft gear that underlies and is fastened to the lower side of the corresponding angle iron and inner and outer draft lugs that are fastened to the upright side of this angle iron, each carrier and the corresponding draft lugs being integrally formed in one 90 piece.

2. In a car structure, the combination with a draft gear; of two wooden center sills; two angle irons, each having an inner upright and a lower outwardly extending side and individual to and receiving one of said sills at the lower inner longitudinal corner of such sill; and a structure individual to and carried by each angle iron and comprising a carrier for the draft gear that underlies and is fastened to the lower side of the corresponding angle iron and a draft lug that is fastened to the upright side of this angle iron, each carrier and the corresponding draft lug being integrally formed in one piece.

3. In a car structure, the combination with a draft gear; of two wooden center sills; two angle irons each having an inner upright and a lower outwardly extending side and individual to and receiving one of said sills at the lower inner longitudinal corner of such sill; a structure individual to and carried by each angle iron and comprising a carrier for the draft gear that underlies and is fastened to the lower side of the corresponding angle iron and inner and outer draft lugs that are fastened to the upright side of this angle iron, each carrier and the corresponding draft lugs being integrally formed in one piece; and a body bolster, the carriers being inwardly extended to engage said bolster.

4. In a car structure, the combination with a draft gear; of two wooden center 130

sills, two angle irons, each having an inner upright and a lower outwardly extending side and individual to and receiving one of said sills at the lower inner longitudinal corner of such sill; a structure individual to and carried by each angle iron and comprising a carrier for the draft gear that underlies and is fastened to the lower side of the corresponding angle iron and a draft lug that is fastened to the upright side of this angle iron, each carrier and the corresponding draft lug being integrally formed in one piece; and a body bolster, the carrier being inwardly extended to engage said bolster.

5. In a car structure, the combination

with two longitudinal draft sills; of a draft gear including a coupler shank, motion resisting means, and a key assembling said shank and motion resisting means, one of said sills having an opening therein through which said key may be passed in the process of placing it; and an obstruction sufficiently covering said opening to prevent withdrawal of said key and lying against the inner upright face of the latter sill and substantially wholly to one side of this face.

In witness whereof, I hereunto subscribe my name this fourth day of April, A. D., 1922.

HERMAN C. PRIEBE.
